UNITED STATES PATENT OFFICE.

CHARLES KAESTNER, OF CHICAGO, ILLINOIS.

MASH-TUB.

SPECIFICATION forming part of Letters Patent No. 241,992, dated May 24, 1881.

Application filed March 8, 1881. (No model.)

To all whom it may concern:

Be it known that I, CHARLES KAESTNER, of Chicago, in the county of Cook and State of Illinois, have invented a certain new and useful Improvement in Mash-Tubs, of which the following is a specification.

My invention relates to revolving stirrers for mash-tubs; and it consists in the peculiar manner of mounting the spindle and sleeve which carry the stirrer-arms in the mash-tub, as fully hereinafter explained, and pointed out by the claim.

In the accompanying drawing, forming a part hereof, the mash-tub is shown in vertical section and the stirrers and mechanism for driving them in elevation and partial section.

A is the mash-tub, of usual construction, and supported in the ordinary manner. It contains two sets of stirrers, one having fingers, which stir the mash at the sides of the tub, and the other revolving within the first at greater speed, and throwing the mash outwardly at the same time that it is stirred.

B B are the arms for the outer stirrers, which arms (preferably three in number) are bolted to a hub-plate, a. Each arm B is provided with a number of angular fingers, b, which project downwardly from the same to near the bottom of the mash-tub, and occupy about half the length of each arm, commencing from its outer end and extending about half-way to the center of the tub. These fingers present angles forward in the direction of their motion, in order to better divide the mash. The hub-plate

a is secured to the upper end of a vertical spindle, C, which is stepped on a journal-box, c, below the tub, and rises through such tub to near the top of the same. The spindle C, near its lower end, has a bevel-gear, d, which meshes with a bevel-gear, e, on a horizontal shaft, D. The shaft D is journaled in suitable boxes, and carries an iron wheel, f, which rests on a paper friction-wheel, g, secured to the driving-shaft or line-shafting E. The iron wheel is adapted to be lifted off of the paper wheel in the well-known manner, so that the stirrers of the mash-tub can be disconnected from the power when desired.

F F are the arms of the second stirrer, (preferably two in number,) which are secured to a hub-plate, h, mounted on the upper end of a sleeve, G, which surrounds the spindle C and

extends down through the bottom of the tub. The sleeve G does not rise up to the hub-plate a, and the arms F are only about half as long as the arms B, so that they will clear the inner fingers on the arms B in operation. The arms F have angular fingers i, similar to the fingers b, but shorter. The fingers i, however, occupy all of the available space on the arms F, being set the required distance apart from the outer to the inner ends of such arms.

Below the mash-tub the sleeve G carries a plain gear-wheel, k, which meshes with a larger gear, l, on a vertical spindle, H, arranged parallel to the spindle C. The spindle H also has a smaller gear, m, which meshes with a larger gear, n, on the spindle C above the bevel-gear d. The gears k l m n are so proportioned that the central stirrers will be revolved at twice the speed of the outer stirrers, the outer stirrers making about ten revolutions a minute, while the inner stirrers make twenty revolutions in the same time. This train being composed of four gears, the motion of the sleeve G is in the same direction as that of the spindle C.

Instead of having the sleeve G driven by the gears k l m n, it may be operated by an equivalent but somewhat different arrangement of gears, which gears are shown in the drawing by dotted lines to the right of the spindle C and sleeve G.

To prevent any liquid from leaking through the tub around the sleeve G, I surround such sleeve by a hollow standard, I, which is secured rigidly and tightly to the bottom of the tub. At its upper end the standard I is provided with a stuffing-box, K, which guides the sleeve, besides serving to keep the mash from working down between the sleeve and standard. The sleeve G, at its upper end, is also provided with a stuffing-box, L, which guides the spindle C and prevents the mash from getting into the sleeve G.

What I claim as my invention is—
In a mash-tub, the combination, with the stirrer-arms B F, the spindle C, and sleeve G, of the hollow standard I and the stuffing-boxes K L, substantially as described and shown.

CHARLES KAESTNER.
